(57) **CLAIM**

The ornamental design for a braided stick pet toy, as shown and described.

DESCRIPTION

FIG. 1 is a front perspective view of a braided stick pet toy embodying my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top view thereof;

FIG. 7 is a bottom view thereof; and,

FIG. 8 is a front elevational view similar to FIG. 2, now illustrating a second embodiment of FIG. 1.
